GANG VALVE FOR AN AQUARIUM OR THE LIKE

Abby Halpert, Brooklyn, N. Y.

Application March 21, 1957, Serial No. 45,387

Term of patent 14 years

(Cl. D91—2)

Fig. 1.

Fig. 2.

Fig. 3.

Fig. 1 is a perspective view of a gang valve for an aquarium or the like showing my new design;

Fig. 2 is a front elevation of the gang valve; and

Fig. 3 is a side elevation of the gang valve.

I claim:

The ornamental design for a gang valve for an aquarium or the like, as shown.
